CLAIM

The ornamental design for a house box, as shown and described.

DESCRIPTION

FIG. 1 is a front, top, left-side view of the house box;
 FIG. 2 is a front elevational view thereof;
 FIG. 3 is a rear elevational view thereof;
 FIG. 4 is a right-side elevational view thereof;
 FIG. 5 is a left-side elevational view thereof;
 FIG. 6 is a top plan view thereof; and,
 FIG. 7 is a bottom plan view thereof.

(Continued)

The broken lines in the drawings depict portions of the house box that form no part of the claimed design.

1 Claim, 7 Drawing Sheets
